LOCK DISPLAY STAND

Adolf Schoepe, Anaheim, Calif.

Application June 8, 1950, Serial No. 10,415

Term of patent 14 years

(Cl. D80—9)

To all whom it may concern:

Be it known that I, Adolf Schoepe, a citizen of the United States, residing at Anaheim, in the county of Orange and State of California, have invented a new, original, and ornamental Design for a Lock Display Stand, of which the following is a specification, reference being had to the accompanying drawing, forming part thereof.

Figure 1 is a perspective view of the lock display stand embodying my new design; and

Fig. 2 is a perspective view of the display stand shown in Fig. 1 but taken from the opposite corner from that in which Fig. 1 was taken.

The broken lines are shown for illustrative purposes only.

I claim:

The ornamental design for a lock display stand, as shown and described.

ADOLF SCHOEPE.
